COMBINED LOCK AND SIGHT APERTURE

Murray Taigman, New York, N. Y.

Application May 17, 1938, Serial No. 208,345

8 Claims. (Cl. 70—431)

The invention relates to a combined door lock and associated sight and speaking tube. It is desirable in some situations as, for instance, in the entrance door of an apartment in an apartment house to have a peep hole in the door so as to be able to see the party at the door before opening the same. Usually, these doors are of expensive stock material and it is difficult, expensive and often ruinous to the appearance of the door to provide an opening therein to form the peep hole. Even after the door has been cut to provide such a peep hole, the hole must be finished and provided with a closure or shutter to maintain the desired finished appearance to both sides of the door. In most apartment houses, the management objects to the disfiguring of the door by the mounting of a peep hole because the doors are usually artistic in appearance and peep holes are usually located in the panel of the door and thus detract from the appearance intended by the designer. However, all doors must be cut or initially constructed to accommodate a lock of some kind so that locks, per se, do not usually detract from the artistic appearance of the door.

The primary object of the invention is to provide a combined speaking and sight tube for a door and which tube is formed as a composite part of the lock and thus can be installed, in position with the installation of the lock avoiding any necessity of cutting an opening especially therefor, and at the same time the invention features the providing of an artistically appearing structure not noticeably distinct from the lock and thus not adding visually to what is usually presented by the conventional appearance of the door.

Broadly, this aspect of the invention is attained by rearranging the lock mechanism in its casing to provide clearance to accommodate an opening therethrough or to utilize the vacant space which occurs in some standard form of door locks to accommodate a tube carried by the lock casing and associated parts and designed to extend entirely therethrough and through the opening in the door which was necessary to accommodate the lock.

In some standard forms of locks the lock mechanism is actuated on the inside of the door by a rotatably mounted knob or handle journaled for rotary movement in the lock casing. In one physical embodiment of the basic invention herein disclosed, it is proposed to make this knob of tubular form to form an eye piece disposed in axial alignment with a barrel carried

by the front or face plate of the lock combination to form a combined sight and speaking tube opening through the lock combination and thus through the door on which it is mounted.

Various other objects and advantages of the invention will be in part obvious from an inspection of the accompanying drawing and in part will be more fully set forth in the following particular description of one form of door lock embodying the invention, and the invention also consists in certain new and novel features of construction and combination of parts herein-after set forth and claimed.

In the accompanying drawing:

Fig. 1 is a view in elevation of a lock and its associated strike as viewed from the inner side of the door and provided with a preferred embodiment of the invention equipped with an eye piece shutter shown in closed position;

Fig. 2 is a vertical sectional view through the lock casing taken on the plane indicated by the line 2—2 of Fig. 3 with part of the cover plate removed and the balance concealing most of the lock controlling mechanism;

Fig. 3 is a transverse vertical sectional view taken axially through the sight tube and taken on the plane indicated by the line 3—3 of Fig. 1 looking in the direction indicated by the arrows; and

Fig. 4 is a view in front elevation of the structure looking at the same from the right hand side of Fig. 3.

In the drawing, there is shown a lock casing 10 of box-like form having on its inner side a steel cover plate 11 demountably secured to the casing 10 by screws 12 and which casing as a whole is mounted on the inner side 13 of a door 14 by exposed screws 15. The casing is provided with the usual locking bolts 16 designed to engage strike 17 carried by the door sill as is usual in such structures. The bolts are actuated through mechanism contained in the casing and which includes a train of gears including at one end a toothed member 18 meshing with an intermediate gear 19 and in turn meshing with a pinion 20. The intermediate gear is fixed to a cylindrical eye piece 21 and journaled in an aperture 22 in the rear wall 23 of the lock casing 10. The gear 19 is threaded on the eye piece and engages in bearing engagement against the inner face of the wall 23, the outer face of which wall is engaged by shoulder 24 formed on the eye piece.

From this construction it is seen that the rearwardly extending portion of the eye piece 25

21 provides a finger turning knob 25 by means of which the gear train is rotated conventionally to actuate the bolts 16. The pinion 20 is provided with a forwardly extending hub 26 which projects through the cover plate 11 for engagement with a cylinder bar 27 and which hub projects into the lock receiving opening 28 cut through or formed in the door. The front end of opening 28 is closed by face plate 29 in the lower portion of which is mounted the key actuated cylinder 30 in the rear end of which is intruded the cylinder bar 27.

It will be understood that this arrangement is of conventional design and arranged so that the proper key inserted in the cylinder will rotate the cylinder bar and thus through the chain of gears and associated parts actuate the bolts 16 conventionally. The face plate is held in place by means of a retaining ring 31 screwed into the rear side of the face plate and engaging annular flange 32 outlining the front end of the opening through the door. The face plate is provided with an opening 33 extending therethrough and which opening is made of as large a diameter as is convenient taking into consideration the size of the lock and the appearance which such an opening would make.

It is herein suggested that one or more bars 34 extend across the opening 33 to form a grid incompletely closing the opening and thus tend to resist the insertion of foreign articles or material into the opening. A barrel 35 of sufficient length to extend between the face plate 29 and eye piece 21 has its forward end externally threaded as shown at 36 and which threaded end extends through and in threaded engagement with the retaining ring 31 and with a recess 37 formed in the face plate 29.

From this construction it will be seen that the barrel, front opening and eye piece are in axial alignment so that the person applying his eye to the eye piece at the left of Fig. 3 can see through the sight tube so provided. In the event that the sight tube is not closed by a glass window or otherwise, the sight tube can be utilized as a speaking tube extending through the door at the lock.

It is desirable when not in use that the sight tube be closed and for this purpose it is provided at its inner end with a shutter 38 pivotally mounted at 39 to one side of the eye piece and held in closed position by snugness of fit or in any other conventional way in which such closures are commonly held in either closed or open position.

By means of a device of the character described, it is possible to provide in a door a peep hole as an inherent part of the lock construction and which peep hole, sight cylinder and speaking tube may be installed in the door without especially providing an opening for the same. As the exterior form of the lock herein disclosed does not materially differ in appearance from conventional forms of a similar make of lock, the peep hole or speaking tube aspect of this structure is not particularly noticeable and the structure can be designed to harmonize with the artistic appearance of the lock and in this way there is avoided objections which have heretofore been made to peep hole constructions in doors.

The structure herein featured can be sold as a stock article to fit doors of varying thicknesses as is usual with known forms of locks, it being simply necessary that the barrel 35 be not too

long, and even if there should be more or less of a gap between the eye piece and barrel it will not interfere with the sighting aspects of the disclosure as space within the lock opening is dark anyhow.

While there have been shown, described and pointed out in the annexed claims, certain novel features of the invention, it will be understood that various omissions, substitutions and changes in the form and details of the device illustrated and in its operation may be made by those skilled in the art without departing from the spirit of the invention.

I claim:

1. A lock including a casing provided with means for mounting it on one side of a door, lock actuating mechanism mounted in the casing and including a train of gears, an end element of said train comprising a pinion journaled in the casing and including a hub projecting from the casing, a face plate provided with means for mounting the same on the opposite side of the door and provided with a key actuated cylinder, a cylinder bar connecting with the cylinder and hub for rotary movement, an eye-piece mounted for rotary movement in the casing and providing an exposed handle, a gear constituting an intermediate element of the gear train fixed to the eye piece to rotate therewith by manual rotation of the eye piece handle, a barrel secured to the face plate, with its bore forming a continuation of the bore of the eye piece and coacting therewith to provide a sight opening extending through the lock casing in offset relation to its lock actuating mechanism.

2. A door lock including parts adapted to extend through and close the opening provided therefore in a door, said lock including control mechanism for actuating the same, said mechanism including a two part tubular member, one part being rotatably mounted in the lock and projecting at one end beyond the same to provide at said end a handle for actuating the control mechanism of the lock, said tubular member having a bore forming a combined sight and speaking tube extending through the lock and by means of which a person can see and speak through the lock without necessity of providing an opening through the door distinct from that necessary for the lock, and a grid incompletely closing the end of the bore remote from the handle to resist the intrusion of foreign articles into the bore.

3. A door lock including control mechanism for actuating the same, said mechanism including a two part tubular member, one part being rotatably mounted in the lock and projecting at one end beyond the same to provide at said end a handle for actuating the control mechanism of the lock, said tubular member having a bore forming a combined sight and speaking tube extending through the door and by means of which a person can see and speak through the door at the lock without necessity of providing an opening distinct from that necessary for the lock.

4. A door lock comprising a casing provided with means for mounting the same on one side of a door, a face plate provided with means for mounting the same on the opposite side of a door, the casing being provided with an eye piece and the face plate provided with a barrel disposed in axial alignment with said eye-piece and coacting therewith when in position on a door to provide a sight opening extending through the lock casing, through the door and through the face plate.

5. A door lock provided with lock mechanism and with a barrel forming a speaking and sight tube for speaking and looking through the lock, said tube provided at one end with a closure and 5 with a grating incompletely closing the other end of the tube, said tube including a part forming an operative portion of the lock mechanism.

6. A door lock provided with lock forming elements including means providing a key hole and 10 a barrel forming a speaking and sight tube offset from said elements for looking through the lock, said tube provided at one end with a manually controlled closure and a casing for certain of the lock forming elements through which the speaking and sight tube extends.

7. A door lock provided with means for mounting the same in position on a door and provided with a barrel extending through the door and 15 constituting a combined speaking and sight tube for looking and speaking through the lock, said

lock including a face plate, a retaining ring secured to the face plate and said barrel secured to the retaining ring.

8. A door lock for doors of different thicknesses, including a face plate provided with means for 5 securing it to one face of the door, a cylinder of a lock having one end mounted in the face plate, said face plate being provided with an opening extending therethrough, a barrel having an unobstructed bore, having one end carried by the 10 face plate and forming a continuation of the opening in the face plate and adapted to extend through the door, a lock casing provided with means for securing it to the opposite face of the door, said casing provided with an eye piece 15 adapted to form a continuation of the barrel, said opening, barrel and eyepiece forming an axially aligned sight opening extending through the door and offset from the lock cylinder.

MURRAY TAIGMAN. 20
